DESIGN.

H. B. HALLOCK.
FAMILY ALTAR.

No. 20,522.

Patented Feb. 17, 1891.

20,522.—FAMILY ALTAR.—Howard B. Hallock, Chicago, Ill., assignor to M. G. Bowen and R. N. Kirk, both of same place. Application filed January 12, 1891. Serial No. 377,546. Term of patent 3½ years.

Witnesses:

Jean Elliott.

Julia Usler.

Inventor:

Howard B. Hallock

By Burton W. Burton

Attorneys:

UNITED STATES PATENT OFFICE.

HOWARD B. HALLOCK, OF CHICAGO, ILLINOIS, ASSIGNOR TO M. G. BOWEN
AND R. N. KIRK, BOTH OF SAME PLACE.

DESIGN FOR A FAMILY-ALTAR.

SPECIFICATION forming part of Design No. 20,522, dated February 17, 1891.

Application filed January 12, 1891. Serial No. 377,546. Term of patent 3½ years.

To all whom it may concern:

Be it known that I, HOWARD B. HALLOCK, a citizen of the United States, residing at Chicago, county of Cook, and State of Illinois, 5 have invented and produced a new and original Design for Family-Altars, which is fully set forth in the following specification, reference being had to the accompanying drawing, forming a part thereof.

- 10 This design is applied to a miniature altar and sanctuary designed for household devotional and sacramental purposes. The table or altar A and the sanctuary and shrine B and the conventional representation of the 15 sacramental symbols C on the paneled front B' of the sanctuary, and designed to represent, conventionally, said symbols as seen within the sanctuary through the entrance-way represented by said panel, are non-distinctive.
- 20 The design consists of the following embellishments applied to said table and sanctuary: first, the architectural embellishment D, of the character of a pavilion, which surmounts the sanctuary and consists of conventional 25 representation of colums D'D', resting upon the sanctuary at its forward edge, flanking or bounding laterally an entrance-way d into the pavilion - space beyond said columns and above the sanctuary, and an ornamental top 30 D², which surmounts the columns and spans the space between them, bounding at the top the said entrance-way d, and a background D³, located at a distance back from said entrance-way and seen between the columns from the 35 front; second, the ornamental candlesticks

E E E E, located two on each side of the sanctuary, and the angular niches E'E', whose floor is above the level of the table and below the level of the top of the sanctuary, and in which two of the candlesticks are located, 40 and the entablatures F F, on which the other two candlesticks are located at the level of the top of the sanctuary on opposite sides of the pavilion-space fronted by the columned entrance-way d. The table, the floor of the 45 angular niches E', and the entablatures F, being at three levels and successively rearward of each other, present the appearance of an ascending stairs at each side of the sanctuary and leading to the pavilion above the sanctuary. A symbolic crucifix G is located in said pavilion; but such crucifix is non-distinctive. 50

I claim—

The design for family-altar herein shown and described, characterized by a pavilion 55 having an ornamental columned entrance-way surmounting the sanctuary, angular niches intermediate between the level of the table and the top of the sanctuary at opposite sides of the latter, and ornamental candlesticks in said 60 niches and in the rear thereof at opposite sides of the pavilion, substantially as set forth.

In testimony whereof I have hereunto set my hand, in the presence of two witnesses, at Chicago, Illinois, this 31st day of December, 65 1890.

II. B. HALLOCK.

Witnesses:

CHAS. S. BURTON,
JEAN ELLIOTT.